DESIGN FOR A CHRISTMAS TREE BELL

Walter F. Reibold, Waterbury, Conn.

Application May 21, 1936, Serial No. 62,759

Term of patent 7 years

To all whom it may concern:

Be it known that I, Walter F. Reibold, a citizen of the United States, residing at Waterbury, in the county of New Haven and State of Connecticut, have invented a new, original, and ornamental Design for a Christmas Tree Bell, of which the following is a specification, reference being had to the accompanying drawing, forming part thereof.

Figure 1 is a view in front elevation of a Christmas tree bell, showing my new design, and

Figure 2 is a top plan view.

I claim:

The ornamental design for a Christmas tree bell, as shown.

WALTER F. REIBOLD.
